UNITED STATES PATENT OFFICE

THOMAS B. KIMBALL, OF MARTINEZ, CALIFORNIA, ASSIGNOR TO SHELL OIL COMPANY,
OF SAN FRANCISCO, CALIFORNIA, A CORPORATION OF CALIFORNIA

PROCESS OF SWEETENING HYDROCARBON DISTILLATES

No Drawing.

Application filed May 31, 1927. Serial No. 195,598.

This invention relates generally to a process or method of removing sulphur compounds from hydrocarbons. It has special application for removing sulphur compounds from gasoline obtained by the cracking process.

It is an object of this invention to devise an effective and economical process for the removal of sulphur compounds, particularly mercaptans, from hydrocarbon distillates.

It is a further object of this invention to devise a novel process for sweetening hydrocarbon distillates, and improving their "doctor" test.

It is another object of this invention to increase the effectiveness of processes for removal of sulphur from normally liquid hydrocarbons by treating the hydrocarbon while in the vapor phase.

Further objects of this invention will appear from the following description in which I have set forth the preferred embodiment of my invention. It is to be understood that the appended claim is to be accorded a range of chemical equivalents consistent with the state of the prior art.

Certain hydrocarbon distillates which are normally in the liquid phase, such as gasoline and kerosene, and particularly those

distillates resulting from the oil cracking process, are rendered sour and unfit for sale by the presence of sulphur compounds. A large part of these sulphur compounds are mercaptans, which must be removed to

sweeten the product. It has previously been proposed to remove these compounds by contacting the liquid hydrocarbon with caustic soda or other alkaline liquid. This treatment is not entirely effective since it leaves a substantial amount of the sulphur compounds in

the distillate, and may not sweeten it sufficiently to effect a negative "doctor" test. As the "doctor" test is affected largely by the presence of mercaptans, it is apparent that

they are not removed to a practical extent by treatment with caustic soda solution while the hydrocarbon is in the liquid phase.

In this invention, treatment of hydrocarbons with an alkaline solution is made much more effective by contacting it with vapors

of the hydrocarbon. The process is carried out in practice by passing the vapors of the hydrocarbon thru a scrubbing tower thru which is maintained a counter flow of an alkaline solution, preferably an aqueous solution of caustic soda. The treating solution is maintained at a temperature which is above the temperature of condensation of the hydrocarbon vapors, so that liquefaction will not occur. The mercaptans and other sulphur compounds in the hydrocarbons combine with the caustic soda to form non-volatile compounds which are carried away by the treating solution. The temperature of the treating agent should not become sufficiently high to cause its substantial vaporization, as this might result in the separation of solids out of the treating liquid.

The treatment of hydrocarbon while in the vapor phase effects results far superior to treatment while in the liquid phase. By actual analysis, gasoline treated while in the liquid phase still contained from 0.16 to .20 percent sulphur compounds and was still positive to the "doctor" test. When the same hydrocarbon was treated by my process, the sulphur compound content was reduced to about 0.06 percent and the "doctor" test was negative or sweet.

The process of my invention is particularly useful in treating "light gasoline" such as absorption gasoline or pressure distillate tops. These gasolines have a series of relatively low boilings points; thus at least 90% of the liquid gasoline will boil at less than 100° C., the boiling point of water. The boiling point at the 90% point, as found by the usual distillation test conducted on gasoline of this character, was 90° C. on one of the gasoline treated in accordance with my process.

In treating distillates of this light character, I preferably utilize an alkaline solution having a boiling point substantially above the 90% point of the gasoline. In one instance I have employed a 16° Bé soda solution containing about 11% NaOH or 12.5 parts on 100 parts of water so that the boiling point of the solution lies between 100°-105° C., averaging about 103° C. While a slight portion

of the heavier fractions of the gasoline being treated may be condensed, the lighter fractions, constituting the major portion of the gasoline, remain vaporized during the treatment. Because of the effect of partial pressures a slight amount of the solution evaporates. However, due to the differences in the vapor pressures of the solution and the gasoline, and since the alkaline solution is preferably maintained below its boiling point, this amount is slight and does not effect the operation of the process as a whole.

I claim:

The process of sweetening cracked light petroleum distillates containing mercaptans to reduce the sulphur content to substantially 0.06 per cent or below comprising: treating unsweetened cracked petroleum distillates containing mercaptans, by counter-currently scrubbing said distillates with a liquid aqueous solution of caustic soda, while maintaining said distillates in the vapor phase, whereby mercaptans are removed from the vapors by the formation of non-volatile compounds in said liquid aqueous solution, said aqueous solution being substantially below its boiling point, and substantially above the condensation temperature of said vapors, under the pressure condition of the system and removing the distillate in the vapor phase from contact with the liquid aqueous solution containing the non-volatile compounds.

In testimony whereof, I have hereunto set my hand.

35 THOMAS B. KIMBALL.
